UNITED STATES PATENT OFFICE.

JAMES N. LEWIS, OF DETROIT, MICHIGAN.

STABILIZER FOR DIRIGIBLE AIRSHIPS.

Application filed December 27, 1921. Serial No. 524,953.

To all whom it may concern:

Be it known that I, JAMES N. LEWIS, a citizen of the United States, and a resident of Detroit, in the county of Wayne and State of Michigan, have invented certain new and useful Improvements in a Stabilizer for Dirigible Airships, of which the following is a specification.

This invention relates to stabilizing means for lighter than air structure air ships.

The objects of the invention are to provide stabilizing means which are automatically operable to maintain the air ship in a substantially stable position.

Further objects are to provide stabilizing means for an air ship of the character named which are manually operable.

Further objects are to obtain stabilizing means for an air ship of the character named which are simple in construction, easily understood and not liable to get out of order.

I have illustrated a construction embodying this invention in the drawing accompanying and forming a part hereof in which,

Fig. 1, is a side elevation of a lighter than air structure air ship, with one side of the nacelle thereof broken away, to show a construction embodying this invention installed therein.

Fig. 2, is a vertical section on line 2—2 of Fig. 1, viewed in the direction indicated by the arrows.

Fig. 3, is in part an elevation, on an enlarged scale, of certain members forming elements of the device; with the electric circuits of which some of said elements are members shown in diagrammatic form and

Fig. 4, is an elevation of a modification of the construction embodying this invention.

A reference character applied to designate a given part indicates said part throughout the several figures of the drawing, wherever the same appears.

The frame of the nacelle of the air ship in which the device embodying this invention is installed, which is illustrated in Figs. 1 and 2, comprises the deck A, the two-part beams B, B, the tie members C, which connects beams B and the side beams D, or ribs D. The ties C which secure the beams B to side beams D, D, are illustrated as attached to said beams and to the ribs D by rivets or bolts E.

F, Fig. 3, indicates a dynamo. G a motor, H, a fuse box. I, I, J and K indicate brushes to motor G. L, represents a base on which

pendulum M swings, as on pivot N. O represents a graduated scale by means of which the swing of pendulum M is observable. m represents the weight or "bob" of the pendulum.

What I term the stabilizer is designated by the reference character P. The stabilizer P, is attached to the car by means of the vertical standards p which extend upward between the parallel beams B, B; and cables p' are attached thereto, and to drums p'', as is indicated in Fig. 2 of the drawing. A plurality of said drums are provided, mounted on shafts p''', and actuated by a motor, as motor G, Fig. 4. When the drums are turned in one direction the stabilizer P is lowered, as indicated by broken lines in Fig. 2 of the drawing, and when turned in the opposite direction said stabilizer is returned to the position in which it is illustrated by full lines in said Fig. 2. When in said last named position it forms the keel to the nacelle.

The motor G is provided with two sets of brushes, arranged so that when the circuit of one set thereof is closed the motor will turn in one direction, and when the circuit of which the other set are members is closed it will turn in the opposite direction.

The conductors q'' and r'' are respectively attached to one set of said brushes and the conductors q''' and r''' are respectively attached to the other set of said brushes. Q represents an electric brush on weight m.

R represents a commutator which is provided with members q, q, and r, r'. When the pendulum M is in the position in which it is illustrated by full lines in Fig. 3, brush Q is in electric contact with and joins, to close or bridge the circuit of which they are elements, members q, r, and in case the pendulum M swings on the pivot N, said brush Q, is adapted to contact with said members q, r' and close the circuits of which said members are elements.

q'' is an electric conductor in electrical contact with members q, q, of commutator R, and with the brushes I, I, of both the sets of brushes (I, J and I, K) of motor G, hereinbefore referred to. R' represents insulating material on which members q, r, r' are mounted. r'', r''', represent electric conductors which are electrically attached to members r, r' of commutator R and to brushes J, K, of motor G which are on the same side of the circuit, (conductor r'' con-

5 nected to brush J and conductor r''' to brush K). R'' and R''' (Fig. 3) represent switches which are interposed in conductors r'' and r''' , respectively, and S represents an abutment on one of the uprights p , which is positioned to open switch R'' as said upright approaches its upward limit of travel, and to open switch R''' as said upright approaches the limit of its downward travel.

10 By this arrangement the circuit in which conductor r'' is a member is opened by the stabilizer P being raised to its extreme upward position; and the circuit in which conductor r''' is a member is opened upon said 15 stabilizer being lowered to its extreme lower position.

It will be observed that the circuit in which said conductor r'' is an element is closed by brush Q being in electric contact 20 with members q and r of commutator R; and the circuit in which conductor r''' is a member is closed when said brush Q, is in contact with either set of the members q and r' of said commutator.

25 It thus occurs that when the air ship rolls or lists to cause the pendulum M to swing on its pivot N so as to carry said brush Q to contact with either one of the members r' of the commutator R the circuit in which conductor r''' is an element is closed and (said circuit being energized by dynamo F) motor G is actuated to lower the stabilizer P. This lowering of the stabilizer will continue until the energized circuit is broken, 30 which may occur by the pendulum returning to its initial position carrying brush Q into electrical contact with member r and the one of members q adjacent thereto on commutator R, or by abutment S opening 35 switch R''' . In whichever of the above recited ways of breaking said circuits said break occurs the circuit in which conductor r'' is a member is closed on the pendulum returning towards its initial position sufficiently to bring brush Q into electrical contact with member r of the commutator.

40 It may thus occur that a small list or roll 50 may start the stabilizer down and before it reaches the limit of its downward travel the air ship may return to its normal position and said stabilizer be returned to its upward (and normal) position.

In the modification which is illustrated in Fig. 4, the stabilizer is lettered P' and consists of two-parts which are respectively pivoted at one end, as at P'' , P''' , and are attached at the other end to the cables p' which extend around the drum p'' .

In this modification only a single drum, 60 p'' and a single motor, G, is required.

I prefer however to use a drum for each part of the stabilizer, P'.

65 By this means the members P', P', may be singly lowered and raised and the principal portion of the weight of said mem-

bers being at the free end thereof when one thereof is lowered at said free end and turning on the pivot of said part, said weight is moved toward the end of the nacelle, as well as downward, and hence the 70 air ship is thereby pointed at an angle from a horizontal plane.

The stop S' is attached to the cable p' in this modification, the standards p of Figs. 1 and 2 not being required.

75 The operation is the same as hereinbefore described relative to stabilizer P, that is, as the pendulum is moved over the commutator R, by the roll of the air ship, the circuit comprising terminals q , r' and brush 80 Q conductor q'' and r''' switch R''' dynamo F, motor G and fuse box H, is closed; the motor G is actuated and the free ends of stabilizer P' are lowered until switch R''' is opened by abutment S'. As the air ship 85 regains its normal position the terminals q , r' , on commutator R are electrically connected by brush Q and the circuit of which brushes I, J of motor G are elements, is closed, and the stabilizer is raised as herein- 90 before described.

To manually operate the stabilizer the pendulum, M, is moved by hand so that the brush on the bob thereof will contact with members q , r' on the commutator.

95

I claim:—

1. In a lighter than air structure air ship, comprising a body member adapted to receive and retain a fluid lighter than the atmosphere surrounding said body and a car 100 member rigidly attached to said body member, the combination of a vertically movable metal bar extending longitudinally on the under side of said car member, and means to automatically control the vertical movement of said bar.

2. In a lighter than air structure air ship, comprising a body member adapted to receive and retain a fluid lighter than the atmosphere surrounding said body member, 110 and comprising a nacelle rigidly attached thereto, the combination with said nacelle of a member extending longitudinally on the under side thereof, and adapted to move adjacent thereto to form the keel thereof, and 115 to be moved therefrom to form a stabilizing member and means to automatically control said movement.

3. In a lighter than air structure air ship, comprising a body member adapted to receive 120 and retain a fluid lighter than the atmosphere surrounding said body and a car member rigidly attached to said body member, the combination of a vertically movable metal bar extending longitudinally on the under 125 side of said car member, and means to automatically control the vertical movement of said bar, said controlling means comprising a commutator, a pendulum, movable brushes actuated by said pendulum arranged to co- 130

act with said commutator, a motor, electric conductors and switches arranged to form a circuit of which said brushes, commutators conductors, motor and switches are elements, means to energize said circuit, and mechanical connections between said motor and said bar.

4. In a lighter than air structure air ship, a nacelle rigidly secured to said airship, 10 the combination of a stabilizer comprising a metal bar extending longitudinally on the outer side of said nacelle, a pendulum, a brush on said pendulum, a commutator adapted to co-act with said brush, a motor, 15 electric circuits comprising said motor, commutator and brushes as elements thereof, and arranged to be successively made and broken by the movement of said brush, and additional means to break said circuits, said 20 motor arranged to actuate said bar, and said

additional means actuated to alternately break said circuits by the approach of said bar to the limits of its travel.

5. In a lighter than air structure air ship, comprising a body member adapted to receive and retain a fluid lighter than the atmosphere surrounding said body member, and comprising a nacelle rigidly attached thereto, the combination with said nacelle of a stabilizing member secured at one end 25 thereof to said nacelle, the opposite end thereof movable, means to control said movement, said controlling means including a pendulum, a commutator, and an electric circuit comprising a motor, and means to 30 energize said motor.

JAMES N. LEWIS.

In the presence of—

CHARLES TURNER BROWN,

SAMUEL M. BOOTH.
